UNITED STATES PATENT OFFICE.

EDMUND L. DES JARDINS, OF CHICAGO, ILLINOIS.

AUTOMATIC OIL CUP.

1,404,347.

Specification of Letters Patent. Patented Jan. 24, 1922.

Application filed November 3, 1919. Serial No. 335,334.

To all whom it may concern:

Be it known that I, EDMUND L. DES JARDINS, a citizen of the United States, and a resident of the city of Chicago, in the county 5 of Cook and State of Illinois, have invented certain new and useful Improvements in an Automatic Oil Cup; and I do hereby declare that the following is a full, clear, and exact description of the same, reference being had 10 to the accompanying drawings, and to the numerals of reference marked thereon, which form a part of this specification.

This invention relates to oil cups, and although not restricted to such use, is particularly adapted for automobiles.

Oil cups as constructed heretofore, have not been easy to regulate for the reason that they either give a continuous stream of oil, or else no oil at all. Further, with the previous forms of oil cups, it was necessary to shut off the flow of oil as soon as the automobile was parked or placed in the garage in order to prevent flooding the parts with oil and the nuisance and waste consequent 25 thereto.

When semi-solid greases are employed, the grease cups provided for their use require constant attention, since the plunger therein must be screwed down periodically 30 to feed the grease into the bearing or other part to be lubricated. The driver of an automobile frequently omits to adjust his grease cups at the right intervals with the result that the parts are not properly lubricated.

It is an object, therefore, of the present invention, to provide an improved means for insuring a steady flow of oil while the car is in operation.

It is also an object of the invention to provide an oil cup which will only feed while the car is in operation.

A further object of the invention is to provide improved means for controlling the 45 flow of oil to surfaces requiring lubrication.

Other and further important objects of this invention will be apparent from the disclosures in the drawings and specification.

The invention (in a preferred form) is 50 illustrated in the drawings and hereinafter more fully described.

Drawings.

Figure 1 is a vertical central section 55 through an oil cup embodying the features of the present invention.

Figure 2 is a plan view of the same.

Figure 3 is a central vertical section through a further form of construction.

Figure 4 is a section on the line 4—4 of 60 Figure 3.

Figure 5 is a section on the line 5—5 of Figure 3.

Figure 6 is a section on the line 6—6 of Figure 3.

Figure 7 is a sectional view of one part 65 of a further form of construction.

Description.

Referring to the form of construction 70 shown in Figures 1 and 2, the oil cup comprises a reservoir 1 with a conical cap 2 secured thereto in any suitable way. Attached to the lower end of the reservoir is a bushing 3 adapted to be connected to the 75 part to be lubricated and having engaged therein the end of a tube 4 leading upwardly above the surface of the contents. Said fitting 3 is flanged outwardly at its upper end and shaped to afford a nut for 80 application of a wrench thereto in applying the oil cup to a part to be lubricated. Centrally arranged within the reservoir 1 is a tube 4 threaded into the aperture of the bushing 3. This tube is arranged to extend 85 above the level of the oil in the reservoir so that oil cannot flow directly thereinto. As the car runs along the road, the oil in the reservoir is splashed about, and a part thereof strikes the conical inner face of the cap 90 2 and is deflected thereby into the upper open end of the tube 4. The flow of oil down the tube 4, resulting from this splashing action, is controlled by means of a wick 5. By constructing this wick of proper material and of suitable density and closeness of weave, the tube 4 may be arranged to deliver a constant quantity of oil. The upper end of the tube 4 is flared outwardly to provide a small catch basin and reservoir above 95 the wick. An aperture 6, normally closed by a pivotally mounted closure 7, is provided for filling the reservoir with oil and is below the upper end of the feed tube preventing the reservoir being filled to a point above 100 the feed tube.

The lower end of the tube 4 is narrowed inwardly and has an outlet aperture therethrough for outlet of oil but prevents withdrawal of the wick therethrough, holding 110 the same in position. The upper portion of the tube 4 is of less outside diameter than

the threaded lower portion to permit insertion and removal of the tube through the fitting 3 for inspection or replacement of the wick when desired.

5 In the construction shown in Figures 3 to 6 inclusive the oil is fed, not only as a result of the upward splashing of the oil in the reservoir into a tube containing a wick, but also by capillary action, since the upper 10 end of the wick is arranged to dip into the body of oil in the reservoir. In this form of construction a glass reservoir 8 is provided, having a bottom 10 and a lid 11 connected to the body portion in any suitable 15 way. Surrounding the glass reservoir 8 is a shell 8^a of brass or other material having view apertures or slots 8^b therethrough. The ends of the shell 8^a have threaded engagement with the top and bottom members 20 10 and 11 and the ends of the glass tube or reservoir are bevelled and seat against gaskets or washers 8^c. The bevelled edges give a large bearing surface affording a tight sealing connection. Centrally arranged and 25 integral with the bottom 10 is an extension priming fitting connection 12 adapted to be threaded into a bearing or the like. Threaded into the upper part of the fitting 12 is the lower end of a pipe 13 extending upwardly 30 through the oil in the reservoir to a point higher than the level of the oil therein. Secured to the upper end of the pipe 13 is a disk 14 having an aperture 15 for the passage of the upper end of the wick 30 there- 35 through. Tongues 16 are stamped downwardly from the material of this disk 14 to hold the end of the wick downwardly in substantially vertical position as shown in Figure 3. With this arrangement, a part 40 of the oil, after being splashed up and around the disk 14, flows into the flared upper end of the tube 13 and is absorbed by the wick. Any oil splashed upwardly onto the top surface of the disk 14 is led 45 into the tube 13 by the grooves 14^a provided in the top surface of the disk.

For admitting oil into the device, an upward semicylindrical extension 20 of the cover 11 is provided having an aperture 22 therein for the spout of an oil can or funnel. Normally, this aperture 22 is closed by a 50 hollow plug 21 slidable within the part 20. This plug 21 is provided with lateral extensions 23 turned inwardly at their ends, as at 26. Slots are formed in the end portions 26 for the passage of a strip 24 of relatively rigid metal secured at 27 and 28 to the part 20 and the cover 11. As this strip 24 is downwardly inclined towards the plug as the latter moves inwardly, its inner end is pressed upwardly as the result of the engagement of the extensions 23 of the plug with the strip 24. This movement presses the plug firmly against the upper wall of 60 the part 20 and securely seals the aperture 65

22. Normally, the plug is held in place by means of a spring 29 which is passed around the strip so that at one end it bears against laterally turned portions 25 at the end of the strip 24, and at its other end against the inwardly directed ends 26 of the side extensions 23 of the plug 20.

Access to the interior of the lubricator for manipulation of the wick may be had without requiring disassembly of the parts, 70 by pulling the plunger 21 outwardly and inserting a wire, hook or small tool inwardly into the reservoir. The wick may be removed and replaced by one such as shown in Figure 7 if desired by such an operation, 75 and the oil cup may thus be converted from a continuous-feed device to an automatic, and vice versa.

In the construction shown in Figure 7 the wick is not arranged to dip down into the 80 oil, so that the feeding of the oil is solely dependent upon the splashing of the oil up and around the disc 31, but the wick acts as a reservoir.

In the case of stationary engines, means 90 may be provided for imparting sufficient vibration from the engine to the oil cup to produce the desired splashing action.

In all cases, except where the wick dips into the oil reservoir, as in Figure 3, the flow 95 of oil ceases as soon as the vibration of the oil cup, either from the engine or from the movements of the automobile.

I am aware that numerous details of construction may be varied through a wide 100 range without departing from the principles of this invention, and I therefore do not purpose limiting the patent granted hereon, otherwise than necessitated by the prior art.

Claims:

1. An oil feed cup comprising a reservoir, a tube extending upwardly through the reservoir terminating above the level of the oil in the reservoir and a wick in the tube, said wick extending over the edge of the tube and 110 down into the oil, and oil collecting means connected to the top of the tube.

2. An oil feed cup comprising a reservoir, a tube extending upwardly through the reservoir to a point above the level of the oil 115 therein, oil collecting means at the top of the tube, and a wick in the tube passing through the oil collecting means to contact with the main body of oil in the reservoir.

3. An oil feed cup comprising a reservoir, 120 a filling cap on the reservoir, a plug slidable in the cap, a tube extending upwardly through the reservoir to a point above the level of the oil therein, and a wick in the tube, the lower end of the tube being constricted to hold the wick in position.

4. An oil feed cup comprising a reservoir, 125 a tube extending upwardly through the reservoir to a point above the level of the oil therein, and a wick arranged wholly within 130

the tube, said tube having a flaring upper end to provide an auxiliary oil reservoir above the wick.

5. An oil feed cup comprising a reservoir, a tube extending upwardly through the reservoir to a point above the level of the oil therein, a wick arranged wholly within the tube, said tube having a flaring upper end to provide an auxiliary oil reservoir above the wick, and an enlarged threaded lower end threaded into an aperture in the bottom of the reservoir, said lower end being of greater outside diameter than the flaring upper end to allow the tube to be withdrawn downwardly through said aperture.

6. An oil feed cup including in combination a reservoir, a filling cap thereon, a tube in the reservoir, oil collecting means at the top of the tube, a wick in the tube having its end extending out through the oil collecting means and down again into the oil, and a spring-held plug slidable in the filling cap.

In testimony whereof I have hereunto subscribed my name in the presence of two subscribing witnesses.
